UNITED STATES PATENT OFFICE.

ALBERT F. COX, OF CHICAGO, ILLINOIS.

HAIR-Straightening DEVICE.

1,014,952.

Specification of Letters Patent.

Patented Jan. 16, 1912.

Application filed January 16, 1911. Serial No. 602,951.

To all whom it may concern:

Be it known that I, ALBERT F. Cox, a citizen of the United States, residing at Chicago, in the county of Cook and State of Illinois, have invented certain new and useful Improvements in Hair-Straightening Devices, of which the following is a description.

My invention belongs to that class of devices known as hair straighteners, and relates particularly to an instrument for straightening hair and taking the curls or kinks out of hair that is naturally very curled or kinked, and has among its objects the production of a simple, convenient, satisfactory and efficient device of the kind described that may be operated by the user without discomfort or without requiring the services of an assistant. Any suitable preparation may be used if desired either before or after the straightening operation or during the same.

To this end my invention consists in the novel construction, arrangement and combination of parts herein shown and described, and more particularly pointed out in the claims.

In the drawings, wherein like reference characters indicate like or corresponding parts, Figure 1 is a side elevation of my improved device, a portion broken away to show the construction, the open position of the same being indicated by dotted lines. Fig. 2 is a plan view of one of the coöperating parts. Fig. 3 is a cross sectional view of the same taken substantially on line 3—3 of Fig. 2. Fig. 4 is a side elevation of a modified construction. Fig. 5 is a cross sectional view taken substantially on line 5—5 of Fig. 4. Fig. 6 is a cross sectional view of a modified arrangement. Fig. 7 is a top plan of one of the coöperating parts illustrating a modified arrangement for securing the rolls in position, one of the rolls being shown in section, and Fig. 8 is a cross sectional view of another modified construction.

Referring to the drawings, in which my preferred form of device is shown, 1 and 2 represent coöperating mating parts, both of which are extended as at 3 and 4 respectively and the extended ends crossed and pivotally

secured together by means of a pin 5 or its equivalent. On the extended ends are provided handles 6 and 7 of any suitable material, preferably a material that will not readily conduct heat. The coöperating parts 1 and 2 may be closed or brought together, or may be opened or separated by operating the handles 6 and 7, any suitable means being provided if desired for keeping them normally in the desired position. The two coöperating parts 1 and 2 are preferably formed or recessed as shown in Fig. 3 and closed at the ends as at 8—8.

Arranged within the parts 1 and 2, preferably longitudinally thereof, are one or more rotating rods or rollers 9 and 10, which are pivotally secured in position by means of screws 11 or their equivalents provided with extended parts 11¹ for rotatably supporting the rollers.

As most clearly shown in Fig. 1, the rollers 7 are extended as at 12 from the body of the roll, so that the entire end portions of the rollers do not bear against the walls 8, thereby reducing the friction.

In Figs. 1, 2 and 3, I show two rollers, 9—9 and 10—10, in each part, the same being arranged so that one roller of one part is arranged between and coöperates with the proximate rollers of the other part.

The parts 1 and 2 substantially inclose the rotatable rolls and as the device is drawn through a quantity of hair, the hair other than that being acted upon between the rotatable rolls is prevented from becoming entangled with or wrapping around the rotatable rolls, by the parts 1 and 2. Each of said parts 1 and 2 is substantially semi-cylindrical in cross section, so that when the parts are brought together, a structure substantially circular in cross section is presented, which can be drawn through the hair with little friction or pulling of the hair.

Fig. 4 illustrates the use of non-rotatable parallel rods or bars 14 and 15, in place of the rotatable rollers or rods which are secured in the mating parts 1 and 2 by means of screws 16. In the case where the non-rotatable rods are employed they are preferably highly polished to decrease friction, so that the hair will easily slip through, as

hereafter described. To prevent too great a pressure on the hair, or for facilitating opening the device, I show a spring 17 arranged between the extensions 3 and 4 of the handles, it being understood that the same may be of any style and be applied to the construction shown in Fig. 1, if desired. Where rods are used instead of the rotatable rollers previously described, I preferably 10 form them cylindrical, or so that they have the convex faces similar to the rollers.

In the construction shown in Fig. 6, I show an arrangement of three rollers 18—18 and 18¹, it being understood that these may 15 be either rollers or bars, as heretofore described.

Fig. 7 of the drawings illustrates a modified arrangement for securing the rollers in position, in which view, 19 represents rollers arranged in one of the parts, which are supported and secured in position by means of bolts 20 extending between the walls 8—8 throughout the length of the rollers or bars. It will be noted in this figure that I have 25 shown the handle 4 extending at an angle, it being understood that the opposite part is similarly formed so that the angle of the rollers relative to the handles is changed some.

30 In Fig. 8 is shown an arrangement of two rollers or rods, as the case may be.

In operating the device the rollers or bars are preferably heated to the desired temperature, by any suitable source of heat, the 35 mating parts 1 and 2 having been previously opened so as to facilitate the heating. Any special preparation may be applied to the hair, either before or after using the device, or during the using if desired, as before mentioned, but I do not wish to be understood as implying that the same is necessary. A lock 40 of hair is then placed between the rollers or rods in the parts 1 and 2 and the parts closed and maintained closed by the desired pressure on the handles 6 and 7; the device is then drawn toward the free ends of the hair. If the free end of the hair is held by the 45 user the straightener may be operated back and forth between the ends, thereby thoroughly ironing or mangling the hair so as to straighten it, but if the free end is not held, then the same may be moved up so as to engage the hair near the head, and then drawn away, the operation being repeated. 50 The rollers being free to rotate, do not grip the hair or engage it too firmly with an excess of pressure so as to pull it out by the roots, or discomfort the user, but, on the contrary, roll back and forth very effectively, accomplishing the result desired. As 55 before mentioned, where the non-rotatable rods or bars are used, they are preferably highly polished to avoid excessive friction or pull on the hair. The rollers or rods by

extending longitudinally the mating parts 65 rather than transversely, permit the hair to be drawn through and extended transversely to the parts, so that the operation or movement of the device is not interfered with or limited by the handle part interfering with 70 the hair. However, I do not wish to be understood as limiting myself to any particular arrangement of the rollers or bars, as they may be varied in position from that shown relative to the handle. By making 75 the mating parts recessed or box-shaped, as shown, the heat is maintained in the rollers or rods for a longer time than if they were more exposed.

It is, of course, obvious that the device 80 may be so constructed that the rolls may be removed from the recessed parts for heating, in which case they might be either pivotally or slidably connected so that they could not become separated or mislaid. 85 (Construction not shown).

Having thus described my invention, it is 90 obvious that various immaterial modifications may be made in the same within the scope of the appended claims without departing from the spirit of my invention, hence I do not wish to be understood as limiting myself to the exact form, arrangement, construction or combination of parts herein shown and described, or uses mentioned. 95

What I claim as new and desire to secure by Letters Patent is:—

1. A device of the kind described, comprising the combination of recessed coöperating parts and means for separating and bringing said parts together, each part being provided with a rotatable roller mounted in the recess thereof. 100

2. A device of the kind described, comprising the combination of coöperating mating parts each part being provided with a pair of rotatable rolls extending longitudinally thereof, said pairs of rolls being arranged to lie parallel in proximity to each other with one roll of each pair positioned between the rolls of the other pair when the mating parts are brought together, and means for bringing said mating parts together with the pairs of rolls in proximity to each other. 110

3. A device of the kind described comprising the combination of coöperating mating parts, said parts being extended and crossed to form handles, and means for pivotally securing the extended parts together, each coöperating part being recessed and provided with a plurality of rollers rotatably mounted therein, the ends of said rollers near the end walls of the recesses being reduced in size to lessen the friction between the ends of 120 the rollers and said parts. 125

4. A device of the kind described, comprising coöperating parts, each part including a

hollow shell substantially semi-cylindrical in cross section, and a roll mounted in the shell and extending longitudinally thereof, and means for bringing said parts together with the rolls in proximity to each other to grasp a lock of hair therebetween.

In testimony whereof, I have hereunto

signed my name in the presence of two subscribing witnesses.

ALBERT F. COX.
